UNITED STATES PATENT OFFICE.

CECIL J. SWAIM, OF MONTREAL, QUEBEC, CANADA.

ATTACHMENT FOR TYPE-WRITERS.

1,106,120.

Specification of Letters Patent.

Patented Aug. 4, 1914.

Application filed January 22, 1912. Serial No. 672,713.

To all whom it may concern:

Be it known that I, CECIL J. SWAIM, of the city of Montreal, in the Province of Quebec and Dominion of Canada, have invented new and useful Improvements in Attachments for Type-Writers, of which the following is a full, clear, and exact description.

This invention relates to improvements in copying attachments for typewriters and is particularly adapted for billing or invoicing.

The object is to provide a device whereby a number of copies may be made at one writing without the use of carbon paper or the like.

A further object is to provide means for making a plurality of connected copies on a single ribbon of paper.

20 A still further object is to provide an attachment so arranged that a summary of all bills or invoices will be automatically made at the same time as the original bills.

Another object is to provide means for 25 automatically shifting the paper at each shift of the carriage.

The apparatus for accomplishing the above objects consists of a framework mounted on the platen spindle of the typewriter at its front end, and supported at its back end on a track attached to the typewriter frame. The rear portion of the framework carries a roll of paper which is fed up and down in front of the platen a suitable number of times, an ink ribbon being interposed between each layer of paper. The paper finally passes between a pair of discharging rolls which are arranged to eject the paper with great rapidity. That portion of the framework which supports the paper in front of the platen is made to move as a whole in order that the several layers of paper may be shifted up for each line of writing without causing any relative movement between the layers. This shifting device is automatically operated by the shifting mechanism of the typewriter carriage, and a second shifting device is provided to return the movable paper to its original position on the completion of an invoice, such second shifting device being arranged to simultaneously operate the typewriter carriage and platen.

In the drawings which illustrate this invention and throughout all the figures of 55 which similar numerals refer to corresponding parts:—Figure 1 is a right hand end elevation of the attachment in position on a typewriter. Fig. 2 is a front elevation of the device. Fig. 3 is a partial left hand end 60 elevation. Fig. 4 is a diagram illustrating the arrangement of the paper. Fig. 5 is a sectional view on the line 5—5, Fig. 1, and shows the locking and unlocking mechanism of the movable frame. Fig. 6 is a 65 plan view of the locking mechanism. Fig. 7 is a fragmentary detail view of the discharge roll opening mechanism. Fig. 8 is a left hand side elevation showing the device in normal position. Fig. 9 is a side elevation 70 of frame 32 in raised position. Fig. 10 is an inside elevation of frame 31 showing arrangement of ribbon guide.

Referring more particularly to the drawings, 11 designates the frame of a typewriter provided with tracks 12 upon which the carriage 13 travels. The platen roll 14 is mounted by means of a spindle 15 on a framework 16 which is carried by the carriage and is vertically movable with respect thereto. A pressure roll 17 is connected to the frame 16 by means of links 18 so as to be movable toward and away from the platen roll. One end of the platen roll is provided with a ratchet toothed wheel 19 which is engaged by a pawl 20 pivotally mounted on the fine spacing lever 21 whenever the carriage is returned, in order that the platen will be automatically rotated at each return of the carriage. This mechanism relates to the typewriter proper and forms no part of this invention, but is described merely to give a clear understanding of the attachment and operation of the mechanism hereinafter described.

An arm 22 is fixed to each end of the carriage and extends rearwardly a suitable distance, and is connected to a suitable support 23 provided with slots 24 in which the spindle 25 of a roll 26 of paper is journaled. The weight of the paper does not come on the typewriter carriage, but is supported by a special carriage 23 traveling on a track 26 which is in turn supported by arms 26^b, which extend rearwardly from 105 the typewriter frame. It will thus be seen

that the arms 22 serve merely to move the paper roll simultaneously with the movement of the carriage. In order to prevent the roll 25 from turning too freely and producing a slackness of paper in the machine a drag bar 27 is provided, the ends of which engage in slots 28 formed in the supports 23. This drag is pressed continually against the paper by means of spiral springs 29 which are tensioned between the supports and the upper ends of standards 30 attached to the drag, as the paper roll is used and diminishes in size. The drag drops down in the slots 28 and practically constant pressure is maintained on the paper by means of the springs 29. While this particular structure has been described, it is obvious that many other forms of drags or brakes may be used without departing from the spirit of the invention.

The copy making mechanism consists primarily of a fixed frame 31 and a vertically movable frame 32 carried thereby at each end of the platen. The fixed frame consists of a plate having a boss or hub 33 through which the platen spindle 15 passes. This plate extends rearwardly from the carriage and is provided at its rear extremity with one or more ink ribbon spools 34 having a small ratchet toothed wheel 35 fixed thereto. A pawl 36 is pivoted to the frame and engages the teeth of the wheel 35 so that the spool may normally be revolved in one direction only. A small operating crank 37 is provided for the spool. It will be understood that the frames 31 at each end of the platen are exactly similar and that each frame carries one or more ribbon spools. By actuating either of the cranks 37, controlling the wheels 35 at opposite ends of the machine, the winding of the ink-ribbon may be tensioned to any desired degree. The ink ribbons 38 are shifted by lifting one of the pawls 36 and turning the crank 37 at the opposite end of the carriage. The number of ink ribbons used depends entirely upon the number of copies which it is desired to make. In the drawings only two ribbons are shown wound on a single spool, but it may be preferred to wind only one ribbon on each spool. The ribbon guide 39 is attached to each frame 31 in line with the ribbon spool, said guide sloping down to approximately the level of the printing point. The lower end of the guide is folded under on itself, the fold being at an angle of approximately 45°. It will thus be seen that the ribbons 38 passing down through the guide will be turned through an angle of 90°, *i. e.*, from vertical to horizontal movement, the ribbons being maintained in substantially a vertical plane. In order to hold the ribbons in position in the guide, the edges of the same are turned over adjacent the fold as indicated at 40. The rib-

bons pass from the spool at one end of the machine, through the guide, across the front of the platen in line with the printing point, and through the second guide to the spool at the opposite end of the machine. The forward extremity of each frame 31 is provided with a downwardly projecting arm 41 having a plurality of vertical slots 42 formed therein one above the other.

The movable frame 32 is substantially L-shaped the long arm being vertical and provided with a plurality of screws 43 which operate through the slots 42 of the fixed frame and hold the movable frame in position. The shorter arm of the movable frame extends rearwardly. The lower extremities of the movable frame 32 are connected by a bar or idler roll 44, and again near the top by a second bar or roll 45. The co-operating discharge rolls 46 and 47 are mounted between the frames 32 above the roll 45. The front roll 46 is journaled directly in the plate 32 and is provided at one end with a pinion 48, which meshes with a suitable larger gear 49 journaled on the right hand plate 32 and provided with an operating crank 50. The back roll 47 is journaled in blocks 51 which slide forwardly or rearwardly in slots 52 formed in the plates 32. These blocks are normally held at the forward ends of the slots 52 so that the rolls 46 and 47 engage by springs 53 which are mounted in suitable housings 54 attached to the plates 32. The compression or load of the springs is rendered adjustable by means of screws 55 against which the rear ends of the springs abut. To open the discharge rolls for convenience in placing paper in the machine, a small cam 56 is pivoted on the spindle of the roll 46 at each end thereof and engage the blocks 51 carrying the roll 47 so as to force the same rearwardly.

A bar 57 is attached at each end to the links 18 carrying the pressure roll 17. The paper ribbon unwinding from the roll 25 passes over the bar 57 and extends upwardly between the platen and all the ink ribbons and around the roll 45. The paper then passes down between the two ribbons 38 and around the bar 44 at the bottom of the movable frame. After passing around the bar 44, the paper passes upwardly a second time and lies between the regular typewriter ribbon 58 and the outer of the two ribbons 38. The paper then passes out of the machine between the discharge rolls 46 and 47. It will be noted that all the rolls and bars over which the paper passes, with the exception of the bar 57, are carried by the movable frame 32. When a single line has been written, this frame is moved upwardly and carries the various layers of paper upwardly without causing any relative movement between the layers. It is obvious that if such

relative movement occurred, one of the copies would have the second line of printing above the first line, while the other two copies would have the second line in its natural position. This will be readily understood by an inspection of Fig. 4.

The mechanism for raising the frame 32 is operated automatically from the platen and line spacing lever at the left hand end of the typewriter. A lever 59 is rigidly mounted at its center on each end of a bar 60 which extends across the typewriter and is journaled in the stationary framework 31. The forward ends of these levers 59 are provided with slots 61 in which the extremities of the roll 45 engage. The rear extremity of the lever 59 at the left hand end of the machine is connected by a link 62 to an extension 63 of the line spacing lever 21. The lower end of the link 62 is provided with a plurality of ratchet teeth 64 which engage a corresponding tooth 65 located between the bifurcations 66 at the end of the arm 63, which bifurcations embrace the lower end of the link 62. A spring 67 is tensioned between the link 62 and arm 63 and operates to hold the teeth 64 and 65 in mesh. It will be readily seen from Figs. 2 and 3 that when the lever 21 is operated, the arm 63 thereof draws down the link 62 and tilts the lever 59 so that the roller 45 is raised and raises with it the entire movable framework 32. Since the levers 59 at each end of the machine are rigidly connected to the bar 60 and are slotted to receive the ends of the roller 45, the lifting movement is applied to each end of the frame 32 with equal force so that there is no strain on the framework itself. The rear extremity of the lever 59 at the right hand end of the machine when it tilts engages under one of a series of latches 68 which project through the frame 31. As the lever tilts, it presses the latch back out of its path until at the moment that the maximum movement of the arm 21 and consequently of the levers 59 is reached, the end of the lever 59 passes the latch 68 which flies out above the lever under the impulse of its spring 69 and prevents the return thereof. When the lever 21 is released, the arm 63 thereof rises and engages the next tooth 64 upon the link 62. It will now be seen that the movable frame 32 has been automatically raised a predetermined distance by the line-spacing lever and locked in such raised position by one of the latches 68. At the next operation of the lever 21 the frame 32 is further raised and locked in the same manner, each raise being the space of a single line. It is obvious that the number of these raises may be increased by increasing the number of latches 68 and correspondingly increasing the number of teeth 64 on the link 62. Each latch 68 is provided with a spindle 70 hav-

ing an eye 71 formed therein. A tripping bar 72 passes through the frame 31, and an arm 73 thereof passes through the eyes of all the latch spindles. It will be noted in Figs. 5 and 6 that the eyes 71 are of sufficient length to allow the retreat of the latches without causing any movement of the trip bar 72.

At the right-hand end of the machine a block 74 is fixed to the stationary frame 31, said block forming the extension of the hub 33 of the frame. A shaft 75 is journaled in this block and extends forwardly and rearwardly, the forward end being provided with an operating lever 76 and the rear end with a cam 77 adapted to force the trip bar 72 inwardly so as to withdraw all the latches 68 and allow the lever 59 to resume its normal position, as shown in Fig. 1. In order to minimize the number of operations required in the use of this attachment, the shaft 75 is provided with platen rotating means. This mechanism comprises a bell-crank lever 78 pivoted at its center on the platen spindle and having one arm thereof provided with a pawl 79 adapted to engage the teeth of a ratchet wheel 80 fixed to the platen spindle. The other arm of the lever 78 is engaged by a small cam or crank 81 carried by the shaft 75. A spring 82 is provided to return the lever 78 to its normal position on the release of the lever 75. Immediately above the roll 46, a knife 83 is provided extending from side to side of the movable frame, and is adapted to provide a suitable edge at which the paper may be readily torn off.

In preparing the machine for operation, the paper ribbon is arranged as previously described and as shown in Fig. 4, care being taken to have the ink ribbons 38 under sufficient tension to prevent their being carried away from the printing point by the movement of the paper. If it is desired to keep a memorandum or statement of all bills or invoices made on the machine, one or more sheets of paper are passed around the platen in the usual manner, care being taken to have a sheet of carbon paper in front of the first of these sheets. If there are copies of the statement to be made, carbon paper will be used for these copies in the usual manner. Assuming the parts to be in the positions shown in the drawings, the first line of an invoice, bill of lading or the like is written. The first copy of the bill is made by the typewriter ribbon 58 while the second and third copies are made by the ribbons 38. Copies of the item are made on the summary sheets by the carbon paper. To prepare for the second line, the line spacing lever 21 is operated in the usual manner to rotate the platen and return the carriage into position to begin the second line. Simultaneously with this movement of the carriage, the mov-

able frame 32 is raised one space and locked by the top latch 68, as previously described. In the same way the second and third lines are written. At the end of the third line in place of using the lever 21 to return the carriage and rotate the platen, the operator uses the lever 76 at the right hand end of the machine. This lever rotates the platen one space as previously described so that the summary statement is carried forward one space by the platen, but at the same time the latches 68 are withdrawn so that the entire frame 32 drops to its original position. The three connected copies of the bill are now ejected from the machine by turning the crank 50. Each of the bills thus made comprises the original and one or more copies, all of which are attached so that there is no danger of loss or confusion. No time is lost in inserting several sheets of paper for each invoice, nor in separating carbon paper from printed copies of the invoice. The lever 76, when operated on the completion of an invoice, moves the platen and consequently the summary one line forward and simultaneously returns the frame 32 to its original position, ready for the commencement of a fresh bill. After a bill has been ejected from the machine it is torn off against the knife 83.

It is obvious that the number of copies made may be increased by increasing the number of layers of paper and consequently the bars over which the paper passes, and also correspondingly increasing the number of ribbons.

A number of changes and modifications may be made in the structure without departing from the broad idea of passing an endless ribbon of paper up and down in front of the platen of a typewriter, and interposing ink ribbons between the layers of such paper.

Having thus described my invention, what

I claim is:—

1. In a typewriter, a platen, means for feeding a strip of paper back and forth in spaced apart layers or folds in front of the platen, and means for feeding ink ribbons between the several layers of the paper.

2. In a typewriter, a platen, means for feeding a strip of paper back and forth in spaced apart layers or folds in front of the platen, and means for shifting all of said layers of paper.

3. In a typewriter, a platen, means for feeding a strip of paper back and forth in spaced apart layers or folds in front of the platen, and means for simultaneously feeding a second sheet of paper.

4. In a typewriter, a typewriter carriage, a platen, means for feeding a strip of paper back and forth in spaced apart layers or folds in front of the platen, means for simultaneously feeding a second sheet of

paper, shifting mechanism for moving all of said connected folds and means for simultaneously shifting said second sheet.

5. In a typewriter, the combination with the typewriter carriage and a platen, of means mounted on the carriage for feeding a ribbon of paper back and forth in spaced-apart layers or folds in front of the platen, means controlled by the platen rotating mechanism for shifting said paper feeding device, and means for automatically locking the paper feeding device in such shifted position.

6. In a typewriter, the combination with the typewriter carriage and a platen, of means mounted on the carriage for feeding a ribbon of paper back and forth in spaced-apart layers or folds in front of the platen, means controlled by the platen rotating mechanism for shifting said paper feeding device, means for automatically locking the paper feeding device in such shifted position, and a manually operated device for releasing said locking means and simultaneously rotating the platen.

7. In a typewriter, the combination with the typewriter carriage, a platen line-spacing mechanism, of mechanism mounted on said carriage and arranged to feed a ribbon of paper back and forth in front of the platen, means operated by the line-spacing mechanism for moving the paper feeding device in one direction at each shift of the platen, means for locking the feeding device after each movement, a device for returning the paper feeding device to its original position and simultaneously rotating the platen, and rolls for ejecting the paper ribbon from the feeding device.

8. In a typewriter, the combination with a typewriter carriage and platen, of a paper roll holder connected to the carriage, a track supporting said paper roll holder, means mounted on the carriage for feeding paper from the roll back and forth in front of the platen, means for raising said paper feeding means simultaneously with the rotating of the platen, latches arranged to lock said paper feeding means at each step of its rise, a cam arranged to withdraw all of said latches whereby the paper feeding means will return to its original position, and a cam operating shaft arranged to rotate the platen simultaneously with the return of the paper feeding means.

9. In a typewriter, the combination with the typewriter carriage and platen, of a paper roll holder connected to and arranged to move with the typewriter carriage, a supporting track for said paper roll holder, a framework rigidly mounted on the carriage, a second framework slidably mounted on said rigid framework, rollers in said second framework arranged to feed paper back and forth in front of the platen, ribbon feeding

mechanism mounted on the stationary framework arranged to feed ink ribbons intermediate the layers of paper in front of the platen, a shaft journaled in said rigid frame work, levers fixed to said shaft and connected at one end to the movable framework, a connection between one of said levers and the platen rotating mechanism, and

a latch mechanism coöperating with the other of said levers.

In witness whereof I have hereunto set my hand in the presence of two witnesses.

CECIL J. SWAIM.
